PRESS CONTROL MECHANISM

Angus F. Hanney, Norwood, Ohio, assignor to
The American Laundry Machinery Company,
Norwood, Ohio, a corporation of Ohio

Application August 29, 1935, Serial No. 38,401

12 Claims. (Cl. 68—9)

This invention relates to control mechanism for pressing machines and more particularly to a mechanism designed for the safe control of pressing machines of the type utilized in ironing garments and laundry goods.

My present invention provides a novel control mechanism for that type of pressing machine in which one member is moved to position adjacent the other and held there while fluid pressure actuated mechanism moves the other pressing member to finally close the machine. My control mechanism provides means for relieving the pressure in this fluid pressure actuated mechanism at such times as the two pressing members are not in proper pressing position opposed to each other.

The control mechanism here disclosed is particularly applicable to that type of pressing machine in which the pressing engagement between the coacting members is provided by the expansion of a diaphragm member and wherein over-expansion of the diaphragm member would be harmful in that it might disrupt the diaphragm member or injure an operator or both. To this end my control mechanism provides a novel means for relieving the pressure beneath such a diaphragm member except when the opposed pressing member is in position to limit the expansion of the diaphragm member.

Another feature of my improved control mechanism is the safe control of pressure in a diaphragm actuated pressing member wherein the pressing machine is arranged to bring a coacting member into position adjacent, but not in pressure contact with, the diaphragm actuated member and wherein the pressing member opposed to the diaphragm member is biased away from it, it being possible in this type of machine to explode the diaphragm if the opposed pressing member should accidentally be removed.

Another feature of my invention is the novel structural arrangements for the pressure control of motive fluid within a pressing member which includes a diaphragm-like movable wall.

In the drawing, Fig. 1 is an end elevation partly in section of a pressing machine embodying my invention and with the control mechanism shown somewhat diagrammatically; Fig. 2 is a plan view of one of the pressing members of Fig. 1 partly broken away to show the structure of the parts; Fig. 3 is a partial view of the pressing members of Fig. 1 showing the same when the pressing machine is normally closed; while Fig. 4 is a view similar to Fig. 3 showing the posi-

tion of the parts with the press opened and with the pressure control device in operation.

Certain features of my invention are applicable to pressing machines where one of the pressing members is moved toward the other by any fluid actuated means and where it is desired to limit any undue movement of the pressing member beyond that normally required to close the press. However, I have chosen to illustrate my device as applied to a pressing machine in which the final pressure between the pressing elements is supplied by a flexible and distensible diaphragm member because great danger is involved upon over-expansion of such a diaphragm member. In the form shown on a frame 10 is mounted a pressing bed indicated generally at 11 and which comprises a base member 12 which carries a diaphragm member 13 which might be a completely closed flexible chamber or bag but which in the present embodiment forms a fluid-tight chamber by securing the diaphragm at its edges 14 to the base 12 in a fluid-tight manner so as to form a chamber 15 between the diaphragm and base. Pressure fluid is supplied to this chamber from a source of supply 16 and through a valve casing 17 and conduit 18. The valve casing 17 houses a normally closed inlet valve and a normally open outlet valve mounted on a common stem for actuation by manual 17a and detent mechanism is shown at 17b for holding the valves in actuated position upon movement upwardly of manual 17a.

Means is provided for relieving the pressure within chamber 15 upon over-expansion of the diaphragm. To this end a valve is arranged to relieve the pressure within the chamber 15, this valve comprising parts adapted to open the valve upon sufficient relative separating movement between the diaphragm and base. The arrangement shown comprises a valve which includes a valve seat 19 and a coacting valve disk 20, the parts being housed in a suitable casing 21. The casing 21 and the seat 19 are substantially rigid with the base 12 and the disk 20 has an operative connection with the diaphragm 13 by means of a valve stem 22 which carries at its upper end a flat head 23. Secured to the under surface of the diaphragm is a plate 24 having a notch 24a adapted to receive the valve stem 22 so that the parts may be separated by relative lateral movement if repairs or removals are necessary. Communication between chamber 15 and the body of the valve casing 21 is by way of ports 25 and an outlet port from the valve casing is provided at 55

26. A spring 27 biases valve disk 20 in a normally closed position and the connection between the head 23 and plate 24 is arranged to provide a lost motion as shown in Figs. 1 and 3 which lost motion permits normal expansion of the diaphragm 13 with reference to the base 12 such as is necessary in a usual pressing operation but which is taken up in the case of over-expansion of the diaphragm member as illustrated in Fig. 4, whereupon the parts 23 and 24 engage so that disk 20 is lifted from its seat 19.

The pressing machine includes a suitable pressing head 28 adapted to coact with the bed 11. Many forms of head and bed pressing members 15 may be utilized in machines of this type, the embodiment shown being of a type designed to iron men's shirts. The head is carried on a lever 29 which is pivotally supported on the frame at 30 and is moved from open to closed position by 20 toggle links 31 and 32 connected between the rear end of the head lever and the frame. A fluid motor 33 is connected with the toggle links to move them into and beyond straightened position when the head approaches the pressing bed without exerting any substantial pressure thereupon, that is to say, when the head is in the position 25 illustrated in Fig. 3. This motor 33 includes a piston 33a whose rod 33b is connected to the toggle links and the stroke of the motor is sufficient to move the links to beyond straightened 30 position where the toggle mechanism contacts a bumper mechanism 34. A spring 35 biases the pressing head toward open position. A snubber 36 helps to control the movement of the pressing head at both ends of its path of movement. Motive fluid is supplied to motor 33 from a source 37 through casing 38, conduit 39, valve casing 40 and conduit 41. Casing 38 houses a normally closed inlet valve and casing 40 houses a normally closed 40 inlet valve and a normally open exhaust valve. The valves in these casings are actuated by 45 manuals 38a and 40a respectively which are arranged in suitable position at the front of the press and spaced apart so as to require a hand of the operator on each one to actuate motor 33.

With the parts in the position of Fig. 1, the operator arranges the lay of the work upon the bed member 11 either directly upon the diaphragm 13 or a padding lying thereover. She 50 then actuates manuals 38a and 40a to admit pressure fluid to motor 33 straightening the toggle links and moving them into a strut-forming position when the head 28 reaches the position shown in Fig. 3. This is the preliminary closed position 55 of the press and release of either of the manuals 28a or 40a during this period of press operation will result in a returning of the head to open position under the influence of snubber 34 and spring 35. If manual 40a is released the outlet 60 valve in casing 40 will exhaust motor 33, while if manual 38a is released motor 33 will be exhausted through the small vent 33c. To complete the closing of the press the operator pulls upwardly on manual 17a which preferably is 65 located adjacent one of the two spaced safety manuals so as to be actuated by the same hand of the operator. This causes a flow of pressure fluid to chamber 15 and expands diaphragm 13 raising the pressing surface of the bed into engagement with the head. Thereafter manuals 70 38a and 40a may be released as the upward pressure of the bed holds the toggle links 31 and 32 in strut-forming position. Detent mechanism 17b will hold manual 17a in its operated position 75 and therefore manual 17a may be released. At

this time the pressing members are in the position of Fig. 3 in which will be noted that diaphragm 13 has expanded into engagement with the head 28 without taking up the lost motion connection between the parts 23 and 24 so that 5 valve disk 20 remains in engagement with its seat 19. To open the press the operator depresses manual 17a against the action of the detent mechanism whereupon fluid is exhausted from beneath the diaphragm 13 by way of the exhaust valve in casing 17. This deflates the diaphragm and removes the pressure from beneath the head whereupon the mechanism 34, 35 is available to return the parts to their original position.

If through accident or otherwise, pressure 15 should be admitted to chamber 15, as by actuation of manual 17a when the pressing head was in open position as shown in Fig. 4, the diaphragm 13 would be distended, but as the diaphragm moves beyond the normal position necessary to 20 cause pressure engagement as previously described in connection with Fig. 3, this further movement takes up the lost motion between the head 23 and the plate 24 thus exerting a pull upon stem 22 and raising disk 20 from the seat 19 which 25 permits a relief of pressure through conduit 26 either to the atmosphere or other point of low pressure. This same action will take place if the press has been safely closed as shown in Fig. 3 and the head is later inadvertently opened while pressure 30 is still being exerted beneath the diaphragm 13.

My improved control mechanism therefore makes it impossible to expand the diaphragm member 13 in an unsafe manner which might result in 35 destruction of the press or injury to the operator.

My invention is applicable to expandible diaphragms no matter how constructed and is applicable for instance to diaphragms composed of metal or other materials. In the form illustrated the diaphragm is intended to be constructed of rubber or of a combination of rubber and fabric. While the pressure supplied at the source 16 is usually less than that at the source 37 yet the pressure of the fluid against the diaphragm 13 is exerted over such an area that the total force tending to explode the diaphragm is very great and it is against this tendency to rupture the diaphragm that certain features of my invention are directed.

What I claim is:

1. In a pressing machine, a pair of coacting pressing members, one of said members including diaphragm means for moving the pressing surface of said member into pressure engagement with the other of said members, means for holding said members in juxtaposition, pressure fluid means for expanding said diaphragm means, and means for relieving said pressure fluid means responsive to expansion of said diaphragm means substantially greater than that normally necessary for causing pressing engagement between the pressing members.

2. In a pressing machine, a pair of coacting pressing members, means for moving one of said members to a point at substantially a fixed distance from the other of said members and for holding it there, diaphragm means for moving the pressing surface of the other of said members into pressure engagement with the first member, fluid means for expanding said diaphragm means, and means for relieving said fluid means responsive to movement of said diaphragm means substantially beyond said fixed distance.

3. In a pressing machine, a pair of coacting pressing members, means for moving one of said members into position opposed to the other of said members and for holding it there, expandible diaphragm means for moving the pressing surface of one of said members into pressure engagement with the other member, said diaphragm means being normally expansible sufficiently to cause said engagement, fluid pressure means for expanding said diaphragm means, and means for relieving said fluid pressure responsive to expansion of said diaphragm means beyond normal.

4. In a pressing machine, a pair of coacting pressing members, means for moving one of said members into position opposed to the other of said members and for holding it there, expandible diaphragm means for moving the pressing surface of one of said members into pressure engagement with the other member, said diaphragm means being normally expansible sufficiently to cause said engagement, fluid pressure means for expanding said diaphragm means, including a normally closed valve adapted when opened to exhaust fluid from said diaphragm means, and means for opening said valve responsive to expansion of said diaphragm means beyond normal.

5. In a pressing machine, a pair of coacting pressing members, means for moving one of said members into position opposed to the other of said members and for holding it there, expandible diaphragm means for moving the pressing surface of one of said members into pressure engagement with the other member, said diaphragm means being normally expansible sufficiently to cause said engagement, fluid pressure means for expanding said diaphragm means including a normally closed valve adapted when opened to exhaust fluid from said diaphragm means, a part for opening said valve and actuatable by expansion movement of said diaphragm means, there being an operative connection between said part and said diaphragm means, and said connection including lost motion sufficient to permit normal expansion of said diaphragm means without actuating said part.

6. In a pressing element, a base, a member movable relative thereto for causing pressing action, fluid pressure means for causing said relative movement, a normally closed pressure relief valve communicating with said means, and means for opening said valve by relative movement between said base and said member beyond a predetermined amount.

7. In a pressing element, a base, a diaphragm member movable relative thereto for causing pressing action, said member being secured to said base to form a substantially fluid-tight chamber therebetween, means for admitting fluid under pressure to said chamber to expand said diaphragm, a normally closed pressure relief valve communicating with said chamber, and means for opening said valve by relative movement between said base and said member beyond a predetermined amount.

8. In a pressing machine, head and bed pressing members, means for moving said head from open to preliminary closed position, a control member for said means, means for normally returning said head to open position from preliminary closed position upon release of said control member, fluid pressure actuated means for moving the pressing surface of said bed into engagement with said head to finally close the press, said head moving means being held against said returning means when finally closed, and means

for relieving the pressure in said bed surface moving means responsive to movement thereof beyond final closed position.

9. In a pressing machine, head and bed pressing members, means for moving said head from open to preliminary closed position, a control member for said means, means for normally returning said head to open position from preliminary closed position upon release of said control member, fluid pressure actuated diaphragm means for moving the pressing surface of said bed into engagement with said head to finally close the press, said head moving means being held against said returning means when finally closed, and means for relieving the pressure in said diaphragm means responsive to movement thereof beyond final closed position.

10. In a pressing machine, head and bed pressing members, means for moving said head from open to preliminary closed position, a control member for said means, means for normally returning said head to open position from preliminary closed position upon release of said control member, fluid pressure actuated means for moving the pressing surface of said bed into engagement with said head to finally close the press, said head moving means being held against said returning means when finally closed, a control member for said bed surface moving means controlled by the operator, and means for relieving the pressure in said bed surface moving means responsive to movement thereof beyond final closed position.

11. In a pressing machine, head and bed pressing members, means for moving said head from open to preliminary closed position, two spaced safety control members for said means both of which must be operated to effectively actuate said means, means for normally returning said head to open position from preliminary closed position upon release of one of said control members, fluid pressure actuated means for moving the pressing surface of said bed into engagement with said head to finally close the press, said head moving means being held against said returning means when finally closed, a control member for said bed surface moving means controlled by the operator, and means for relieving the pressure in said bed surface moving means responsive to movement thereof beyond final closed position.

12. In a pressing machine, coacting head and bed pressing members, mechanism for placing and holding said head in position adjacent said bed, said bed including a base and a flexible substantially fluid-tight diaphragm carried thereby and forming a fluid-tight chamber for moving the surface of said bed toward said head, means for introducing fluid under pressure into said chamber to expand said diaphragm and cause bed engagement with said head, a normally closed valve controlling communication between said chamber and atmosphere, said valve including relatively movable parts one substantially rigid with said base and the other operatively connected with said diaphragm, whereby said valve may be opened by relative separation between said base and diaphragm, said operative connection comprising a lost motion connection permitting bed engagement with said head without valve opening, and said parts being arranged to open said valve responsive to a relative separating movement of said base and diaphragm beyond that necessary to cause bed engagement with said head.
